(57) **CLAIM**

The ornamental design for a touch panel, as shown and described.

DESCRIPTION

FIG. 1 is a front view of a touch panel in accordance with the invention;

FIG. 2 is a first side view of the touch panel shown in FIG. 1; FIG. 3 is a second side view of the touch panel shown in FIG. 1;

FIG. 4 is a top view of the touch panel shown in FIG. 1;

FIG. 5 is a rear view of the touch panel shown in FIG. 1;

FIG. 6 is a bottom view of the touch panel shown in FIG. 1;

FIG. 7 is a front perspective of the touch panel shown in FIG. 1;

FIG. 8 is a rear perspective of the touch panel shown in FIG. 1;

FIG. 9 is a first rear perspective of the touch panel shown in FIG. 1 depicting an extended support member;

FIG. 10 is a second rear perspective of the touch panel shown in FIG. 1 depicting the extended support member;

FIG. 11 is a first front perspective of the touch panel shown in FIG. 1 partially depicting the extended support member; and,

FIG. 12 is a second front perspective of the touch panel shown in FIG. 1 partially depicting the extended support member.
